UNITED STATES PATENT OFFICE.

ERNEST VON DER LIPPE, OF CHICAGO, ILLINOIS.

RETURN TUBULAR BOILER.

1,360,980.

Specification of Letters Patent. Patented Nov. 30, 1920.

Application filed November 4, 1916. Serial No. 129,432.

To all whom it may concern:

Be it known that I, ERNEST VON DER LIPPE, citizen of the United States, residing at Chicago, in the county of Cook and State of Illinois, have invented certain new and useful Improvements in Return Tubular Boilers; and I do hereby declare the following to be a full, clear, and exact description of the invention, such as will enable others skilled 10 in the art to which it appertains to make and use the same.

In its general aspects, my invention relates to fluid-heating appliances of the general class including boilers, hot water heaters and hot air furnaces, its general aims being to produce a simple, compact and easily controlled heating appliance which will be unusually efficient and which will be practically smokeless even with cheap grades of fuel. For this purpose, my invention aims to produce a heating appliance which will permit of a quick starting of the chimney draft, which will utilize the waste heat of the combustion gases for heating the air supply of the fire box, which will enable this heated air supply to be used effectively both above and below the grate, and in which both the chimney or smoke pipe connections and the air supply may be effectively and simultaneously controlled. More particularly, my invention aims to provide a heating appliance of the class described having upwardly directed tubes leading from the firebox to a combustion chamber, and also having auxiliary tubes extending downwardly from the combustion chamber and connected to a smoke pipe, to provide means for shunting these auxiliary tubes while the fire is being started or forced, to utilize the 40 heat of the gases after leaving the auxiliary tubes for heating the air supply of the firebox, to provide means for conveying this preheated air supply to desirable entrance points located both above and below the grate, and means for simultaneously controlling the air supply connections of the ash-pit with both the preheating chamber and the outer air; and to provide a construction which will readily enable the baffle-plate or smoke-plate and the hot air supply tubes to be replaced. Further objects 50 will appear hereafter.

While my invention may be employed advantageously with boilers and hot air furnaces of widely varying types, it is particularly adapted for use in connection with a

house-warming appliance and is shown in such an embodiment in the accompanying drawings, in which—

Figure 1 is a central vertical section 60 through a boiler embodying my invention.

Fig. 2 is a horizontal section, taken along the line 2—2 of Fig. 1.

Fig. 3 is a fragmentary horizontal section, taken along the line 3—3 of Fig. 1. 65

Fig. 4 is a vertical diagrammatic view corresponding to Fig. 1 and also showing the simultaneously operable dampers controlling the connections to the smoke pipe and the air supply. 70

In the drawings, an outer cylindrical shell 1 houses an upper plate 2 and a lower plate 3 connected by vertical tubes 4 and 5, these tubes being disposed respectively on opposite sides of a partition 6 which extends vertically downward from the lower plate 3 and which partition forms a back for both the firebox 7 and the ash-pit 8. All of the said tubes open at the top into a combustion chamber 9 which is connected to the smoke pipe 10 by a flue 11 controlled by a damper 12. The lower ends of the rear tubes 5 lead to a smoke chamber 13 which is connected to the smoke pipe 10 by a flue 14 controlled by a damper 15. This smoke chamber is 80 separated by an inclined smoke-plate or baffle plate 16 from the air-preheating chamber 26 which adjoins the partition 6, the plate 16 being preferably made of a good conductor of heat, such as iron. The upper part 85 of the partition 6 has a number of perforations, each of which preferably leads to a short tube 17 projecting into the fire-box and adapted to have the rear end of an air-inlet tube 23 slipped over it. Below the 90 grate 18, the partition 6, may also have an opening 19 controlled by a door 20 and connecting the ashpit 8 with the air-preheating chamber 26. Other doors 21 and 22 control 95 openings leading from the outer air to the air-preheating chamber 26 and the ashpit respectively, and both of these doors may advantageously be controlled simultaneously with the dampers 12 and 15 by means of a suitable connecting mechanism, such as the belt 24 shown in the diagram of Fig. 4.

In starting the heating appliance of the drawings, the various doors and dampers are turned at right angles to the position shown in the diagram of Fig. 4, thus shutting off both the lower smoke pipe connection and the air inlet 21. The air supply 110

then enters through the opening 22 of the ashpit and passes through the grate 18, while the smoke and other products of combustion pass upward through the tubes 4 into the combustion chamber 9 and thence through the flue 11 to the smoke pipe 10, so that there is a quite direct passage from the outer air to the chimney. When the fire is well started, thereby also warming the chimney and starting a strong draft in the latter, the closure elements are moved to the position shown in Fig. 4. This change closes the direct air-inlet 22 to the firebox, but opens the rear air inlet 21, so that the air must pass through the preheating chamber 26 before it can reach the fuel either through the ashpit or through the tubes 23. Likewise, this change closes the direct connection from the combustion chamber to the chimney, but opens the connection through the flue 14 to the lower end of the smoke pipe, so that the gases in the combustion chamber can reach the smoke pipe by first passing through the return tubes 5, after which they impinge more or less against the baffle plate 16, thus conveying some of their heat to the air in the preheating chamber. By manipulating the intermediate door 20, the proportion of air supplied respectively above and below the grate may be varied according to the nature and quantity of the fuel, and in any case the supplying of previously heated air above the grate through the tubes 23 (which tubes preferably have their free ends bent downwardly as shown in Fig. 1) makes it easy to secure practically smokeless combustion even when using a cheap grade of fuel. Besides, the warming of the air supply by conduction both from the baffle plate and from the partition 6 permits of a saving in fuel, so that the heating appliance of my invention permits of both

smokeless and economical operation with very little attention.

However, while I have shown an embodiment having two air tubes 23 supported by a vertical partition and having a body of water 28 as the fluid heated by the tubes 4 and 5, I do not wish to be limited to these or other details of the construction and arrangement herein disclosed, it being obvious that the same might be modified in many ways without departing from the spirit of my invention. Thus, it will be evident that the relative size and number of the tubes in these ducts 4 and 5 may be varied considerably, as long as these tubes with the connecting chamber 9 form a bifurcated passage in which the two arms extend through the fluid chamber and lead at their free ends respectively to the fire box and the smoke pipe.

I claim as my invention:

In a heating appliance, a boiler having vertical tubes extending therethrough, a fire-box and a rear chamber jointly disposed below the boiler and each having some of the said tubes opening into the said fire box and rear chamber respectively, a vertical partition between the fire-box and the rear chamber, an upper chamber connected to the upper ends of all flues, a chimney connected both to the upper chamber and to the rear chamber, a heat-conducting partition extending across the rear chamber, flue connections to the chimney, an air intake for the portion of the rear chamber below the last named partition, and an air duct connecting the last named portion of the rear chamber with the fire-box and opening above the grate in the latter.

Signed at Chicago, Illinois, November 2nd, 1916.

ERNEST VON DER LIPPE
